UNITED STATES PATENT OFFICE.

MARCUS REGINALD ANTHONY SAMUEL AND ALFRED ANDREW LOCKWOOD, OF LONDON, ENGLAND, ASSIGNORS TO THE KARSAM SOAP COMPANY, LIMITED, OF LONDON, ENGLAND.

MANUFACTURE OF SOAP OR MIXTURES CONTAINING SOAP.

No. 918,705.

Specification of Letters Patent.

Patented April 20, 1909.

Application filed October 28, 1907. Serial No. 399,592.

To all whom it may concern:

Be it known that we, MARCUS REGINALD ANTHONY SAMUEL and ALFRED ANDREW LOCKWOOD, manufacturers, subjects of the 5 King of Great Britain, both residing at 12 Minories, in the city of London, England, have invented new and useful Improvements in the Manufacture of Soap or Mixtures Containing Soap, of which the following is 10 a specification.

This invention relates to improved means for incorporating mineral oils with soap or mixtures containing soap such as detergents or lubricants and the like.

15 Various processes have been suggested for incorporating petroleum or like mineral oils with soaps usually by stirring or crutching. It has also been suggested to force more or less volatile substances, including petroleum, 20 while in a gaseous condition into soap or to add them in drops or in the form of a spray while liquid into soap heated to such a temperature that they were immediately volatilized; this process was carried out in a 25 closed vessel and means were provided for carrying off the fumes. In none of the processes suggested could the petroleum be added during the ordinary boiling of soaps in an open pot.

30 According to this invention a suitable hydrocarbon oil which does not appreciably vaporize during the process of soap boiling, such as petroleum kerosene, is introduced in a finely divided or pulverized condition into 35 the soap or saponaceous mixture at a suitable stage of its manufacture. The oil should not during this process be heated to such an extent that it appreciably volatilizes. Any tendency of the oil to volatilize may be 40 also counteracted by supplying it under suitable pressure.

The process may be carried out as follows: 2 parts of tallow or other saponifiable substance are saponified with caustic soda in the 45 usual manner in an open pot. After salting out and while the soap is still boiling in an open condition, an excess of alkali being present, 5 parts of ordinary kerosene burning oil having a flash point of about 73° F. 50 is injected in a finely divided state. The boiling is continued in order to render the mass uniform. It is then allowed to settle and is drawn off in the usual manner. The

soap when cool will solidify and the oil will not separate even if framed at a high temperature. A soft soap is made in the same way—care being taken to add sufficient alkali to bring it into an open condition.

55 In the accompanying drawing Figure 1 is a view partly in elevation, partly in section and with parts broken away, illustrating an apparatus which may be used in carrying out our invention. Fig. 2 is a detailed view of the pulverizer through which hydrocarbon may be passed into the boiling soap.

60 In the drawings *a* is a storage bank containing the mineral oil, *b* a gage provided with a glass front, *c* the outer tube of an injector, *d* a tube for conveying steam or other fluid to the tube *c*, *e* the inner injector tube in communication with the tank, *f* an inner pulverizing chamber filled with woven wire netting or cloth, *g* an outer pulverizing chamber filled with closely woven wire cloth. 75 *h* is the copper or pot.

70 The tank *a*, it will be observed, is located some distance above the pot *h* so that some pressure is produced on the oil while it is being supplied to the pot and this pressure 80 may be such, if necessary, that any tendency for the oil to volatilize at the temperature employed while it is passing through the tube *e* to the pulverizer may be avoided.

85 The mineral oil may be injected in the desired proportion, or a base or stock product containing a large percentage may be made and this may be added or injected preferably in a hot and liquid condition in the desired proportion to the finishing boil 90 of the soap. In some cases this may be found advantageous as prolonged boiling of the oils is avoided and loss by volatilization or evaporation is minimized. Detergents lubricants and the like may be made by 95 adding petroleum to mixtures containing soap in a similar manner.

100 By this process very large percentages of mineral oils may be incorporated with soap and such oils will not separate even after prolonged boiling. Another advantage of this process is that even where fairly large percentages of mineral oil are present a good and sufficient lather is obtainable; as much as and probably more than 20% 105 weight of mineral oil in proportion to the

saponifiable substances used will not prevent a good lather when the temperature of the water rises to the boil.

What we claim is:—

5. 1. In a process for the manufacture of a soap containing permanently emulsified hydrocarbon oil, injecting the hydrocarbon oil in a finely divided condition into a soap mixed with an alkali, the hydrocarbon oil being maintained during the process at a 10 temperature below the point at which it appreciably volatilizes.
2. In a process for the manufacture of a soap containing permanently emulsified hydrocarbon oil, injecting the hydrocarbon oil in a finely divided condition into a soap 15

mixed with an alkali, the hydrocarbon oil being maintained during the process under such pressure and at such temperature that volatilization thereof is prevented.

20

3. In a process for incorporating a hydrocarbon oil with soap, injecting heavy hydrocarbon oil in a finely divided condition into soap mixed with an alkali, the hydrocarbon oil being maintained during the process at 25 a temperature below the point at which it appreciably volatilizes.

MARCUS REGINALD ANTHONY SAMUEL.

ALFRED ANDREW LOCKWOOD.
